UNITED STATES PATENT OFFICE.

HENRY LÉON FISHER, OF CHAZY, NEW YORK.

PORTABLE CAMP-BED.

1,143,374.

Specification of Letters Patent.

Patented June 15, 1915.

Application filed December 24, 1910. Serial No. 599,136.

To all whom it may concern:

Be it known that I, HENRY LÉON FISHER, a citizen of the United States, residing in Chazy, in the county of Clinton and State of New York, have invented a new and useful Improvement in Portable Camp-Beds, of which the following is a specification.

My invention relates to improvements in portable folding cots.

10 The object of my invention is to provide a portable camp cot suitable for military use, which will be strong, efficient and durable, light in weight, small and compact in compass when collapsed, which will be composed of few pieces, and be free from loose or detached parts liable to become lost on the march, and which can be quickly and easily erected for use and collapsed and packed for the march.

20 My invention consists in the means I employ to practically accomplish this object as herein shown and described and more particularly specified in the claim.

In the accompanying drawing, Figure 1 is a perspective view of a soldier's portable collapsible camp cot embodying my invention, the canvas being shown in dotted lines to more clearly illustrate the other parts. Figs. 2 and 3 taken together make the side 25 elevation showing the longitudinal connections of the end frame members detached ready for collapsing or folding. Fig. 4 shows the end members collapsed ready for the canvas cover. Fig. 5 shows the portable 30 cot collapsed and packed ready for the march, the canvas being wrapped around the frame members. Fig. 6 shows one of the end frame members partially collapsed. Fig. 7 shows the brace.

40 In the drawing, A A represent the longitudinal connections between the end frame members B B¹ and C is the canvas suspended between the end frame members.

The end frame members B B¹ are alike and each comprises a pair of posts or uprights b, b, and a pair of diagonal braces b¹ b¹ connected together at their middle by a pivot b², and each pivotally connected by a pin b³ to the upper end of the post or upright b, and each upright b having a slot b⁴ at its lower end to detachably connect it to the lower end of the brace b¹ by means of a rivet b⁵ which is secured to the brace member b¹ at its lower end, the slotted end of the post fitting between the head b⁶ of the rivet and the diagonal brace member b¹. Each of

the diagonal brace members b¹ is furnished at its upper end with an upwardly projecting button b⁷, preferably in a separate piece from the brace member and secured thereto by rivets b⁸.

The longitudinal connections A A between the upright posts b b of the end frame members B B¹ preferably each comprises three bars a a and a¹, the bars a being each pivotally connected at one end with one of the posts b preferably by means of a bracket b⁹ secured by rivets b¹⁰ to the post or upright b and a hinge pin a² which extends through the bar a and through the bracket b⁹. The hinge bracket b⁹ is secured on the inside of one of the posts b of each frame B and upon the outside of the other post b of said frame B so that when the bars a a of the longitudinal connections A A which are hinged to each of the frames B swing down, as indicated by the dotted lines in Figs. 2 and 3, said bars a a will come upon opposite faces of the frame B, and thus not interfere with the collapsing of the frame B, as will be readily understood from Figs. 2, 3, 4 and 6 of the drawing. The bars a a of each longitudinal connection A are connected together by the intermediate bar a¹ by means of rivets or pivot pins a³ a⁴, which engage notches a⁵ a⁶ in the intermediate bar a¹, said bar a¹ having at one end a hole a⁷ for one of the rivets to pass through so that the bar a¹ may be permanently connected to one of the bars a.

The canvas C which is stretched and suspended between the end frames B B¹ is furnished with eyes C¹ through which the buttons b⁷ on the end frames B B pass to removably connect the canvas to the end frames. The end frames B B¹ and connecting bars A are all preferably made of aluminum, and when thus constructed, my complete camp cot, including the canvas may be made very strong and durable and at the same time of a weight not necessarily exceeding five or six pounds.

To collapse and pack my improved military cot for the march, the canvas C is first removed. The connecting bars a attached to one of the end frames, B¹, are then disconnected from the end of the intermediate bars a¹ having the double notches a⁵ a⁶ therein, thus separating the end frames B B¹ from each other. The posts b b of each of the end frames B are then slipped out of engagement with the rivets b⁵ at the lower

ends of the diagonal brace members b^1 , cross brace c is disconnected and folded on to a and then the connecting bars a swing into the position shown in dotted lines in Figs. 2 and 3, the intermediate bar a^1 being interfolded with one pair of bars a , and then each of the end frames B is collapsed in the manner indicated in Fig. 6 into the position shown in Fig. 4, after which the canvas C is wrapped around the folded end frame members B B and secured by the straps and buckles C^2 C^3 attached to the canvas.

A cross brace or member c is preferably provided to extend between the longitudinal bars A, it being preferably hinged at c^1 to one of the cross bars A and connected at its opposite end by a notched flange c^2 on the brace which removably engages a rivet c^3 on the other longitudinal bar A.

20 I claim:—

In a portable, collapsible camp cot, the combination of a pair of end frame members each comprising a pair of uprights and a pair of diagonal braces, said braces being pivoted together at their crossing point and each having an end pivoted to the upper end of one of said uprights and formed at their

other end for detachable connection with the lower end of the other upright, said detachable connection consisting of a pin and slot engagement adapted to tighten when weight is sustained by the cot, connections between said end frames, said connections comprising a plurality of longitudinally disposed sections connected at their ends the end sections being pivotally connected to appropriate uprights, said sections having a detachable connection at a point on each side of the cot which detachable connection consists of a plurality of slot and pin engagements adapted to tighten under weight sustained by the cot, a cross brace between the connections, said cross brace comprising a member pivoted to one of said connections and detachably engaging the other section, which detachable engagement consists of a pin and slot connection arranged to tighten under weight sustained by the cot, and a canvas connected to said end frames.

HENRY LÉON FISHER.
